UNITED STATES PATENT OFFICE.

JOHN T. H. DEMPSTER, OF SCHENECTADY, NEW YORK, ASSIGNOR TO GENERAL ELECTRIC COMPANY, A CORPORATION OF NEW YORK.

ARC-LAMP.

1,091,641.

Specification of Letters Patent. Patented Mar. 31, 1914.

Application filed November 16, 1903. Serial No. 181,299.

To all whom it may concern:

Be it known that I, JOHN T. H. DEMPSTER, a citizen of the United States, residing at Schenectady, county of Schenectady, State of New York, have invented certain new and useful Improvements in Arc-Lamps, of which the following is a specification.

The object of my present invention is to improve the construction and operation of arc lamps.

More particularly my invention relates to arc lamps in which the major portion of the illumination comes from the arc itself as distinguished from those lamps in which the major portion of the illumination comes from electrodes heated to incandescence. In such lamps it has been found that one of the electrodes can advantageously be so constructed and arranged that it will not consume during the normal operation of the lamp, and my present invention contemplates a certain novel construction and arrangement of such a non-consuming electrode.

My present invention also contemplates a novel electrode feed mechanism. This mechanism I have hereinafter illustrated and described as employed in a lamp provided with my novel form of non-consuming electrode, but it is not necessarily in all respects limited to such conjoint use.

These features of novelty, together with others which characterize my present invention, are pointed out with particularity in the claims annexed to and forming a part of this specification.

For the better understanding of my invention reference may be had to the annexed drawings in which I have illustrated one embodiment of my invention.

Of the drawings, Figure 1 is a sectional elevation of an arc lamp; Fig. 2 is an elevation showing part of the mechanism of the lamp; Fig. 3 is a similar view taken at right angles to Fig. 2; Fig. 4 shows a detail of the feed mechanism; Fig. 5 shows the bottom of the lamp casing and the method of supporting the globe; Fig. 6 is a diagram illustrating the circuits of the lamp, and Fig. 7 is a perspective view of the manually operated cross-head for disengaging the clutch.

Referring to the drawings, 1 represents the lamp cap or top, on the upper side of

which suitable supporting means are placed. Binding posts 3 and 3' of ordinary construction are also carried by the cap 1. A tubular member 4 is secured to the under side of the cap 1 by screws 4'. At the lower end 60 of the member 4 a disk-like platform 5 is carried. Posts 6 depending from platform 5 carry at their lower ends another disk-like platform 7. Some distance beneath the platform 7 an annular member 8 is carried by means of the screws 9 which are threaded into the under side of the platform 7. A tubular member 8' extends downward from the inner periphery of the annular member 8 for a purpose to be hereinafter set forth. 65 A circular plate 10, of some material, such as copper, which is a good conductor of heat and electricity, is located in the space between the platform 7 and the annular member 8. This plate is separated and insulated from the platform 7 and annular member 8 by means of the tubular spacing members 11 which surround the bolts or screws 9. From the under side of the member 10 a cylindrical rod or pencil 13 extends forming one of the electrodes of the lamp. 70

The rod or pencil 13 is made out of some material which is a good conductor both of heat and electricity, such as copper, and is secured to the plate 10 in any suitable manner, as by means of a threaded extension of the rod or pencil which is screwed into a threaded opening formed for the purpose in the plate 10. The electrode 13 passes 75 centrally through the annular member 8 projecting below the annular member about as far as does the tubular member 8'. A jacket or layer 14 of mica, or similar material, surrounds the upper portion of the 80 rod or pencil 13 extending down to within a short distance of the lower end of the pencil. Another bushing or tube section 15 of substantially the same length as the rod or pencil, and preferably formed out of porcelain, surrounds the mica jacket and enclosed pencil. It will be observed that the lower end of the pencil 13 is separated from the insulating jacket by an annular space 15'. 85

The lower electrode 16 of the lamp, which may be formed of, or contain, magnetite or titanium carbide, or other material giving a flaming or luminous arc, is held in a socket 17 carried by a cross head 18. The cross head 18 is secured to the lower end of a 90

pair of rods 19 which pass through apertures formed for the purpose in platform 7, annular member 8 and plate 10. Suitable bushings 20 which may be formed out of porcelain or other insulating material serve to insulate the rods 19 from the plate 10. A cross head 18' unites the upper ends of the rods 19. The cross head 18' is secured to the lower end of a rack bar 21. The upper end of this bar is adapted to enter the tubular member 4 with which it operates to form a regulating dashpot. A shaft 22, journaled in bearings 23 carried by the posts 6, carries a spur gear wheel 24 which meshes with the teeth on the rack 21. The shaft also carries a ratchet wheel 25 somewhat larger than the gear wheel 24. A pair of magnet coils 26 are supported by a post or member 27 formed of magnetic material to which their cores 28 are connected by screws 29. The post 27 has an offset portion 28' at its lower end which rests against the upper surface of platform 7. Screws 29' passing through the offset portion of 28' secure it to the member 7. The armature 30 coöperating with the magnet coils 26 is pivoted at 31 in a yoke-shaped support 32 also secured to the upper side of the member 7. A spring 33, having one end secured to 30 a lug formed for the purpose on the post 27 and the other end secured to a similar lug formed for the purpose on the armature 30 below its support 31, normally holds the armature in the position shown in Fig. 2. The outward movement of the armature 30 is limited by a stop 34 which may consist of a projection or extension of one of the cores 28 which passes through a slot or channel formed for the purpose in the armature 30 and is formed with a bend at its outer end. A spring pawl 35, the outer end of which normally engages the ratchet wheel 25, is secured to the upper end of the armature 30. A member 36 loosely pivoted to the armature 30 above the pawl 35 has near its free end a slot, indicated in dotted lines in Fig. 2, and the tooth of the pawl passes through that slot; it also has an offset portion 37 at its outer end. The pawl 35 and member 36 are so arranged that when the outer end 37 of the member 36 is depressed, it engages the pawl 35 and carries it out of engagement with the teeth of the ratchet wheel 25. The teeth on ratchet wheel 25 and pawl 35 are so arranged that when the magnet coils 26 are energized and the armature 30 is attracted the wheel 25 will be rotated in the direction indicated by the arrow in Fig. 2. When the magnet coils 26 are deenergized the armature 30 will return to the position shown in Fig. 2. A dog 38 secured to the under side of the platform 5 normally prevents a rotation of the ratchet wheel 25 in the direction opposite to that indicated by the arrow 35 in Fig. 2.

A spring contact member 39, secured in any suitable manner to the under side of platform 5, is normally in engagement with one end of a contact screw 40 passing through a member 41, also secured to the under side of platform 5. An arm or member 42 projecting from the armature 30 is adapted to engage the lower end of the member 39 and move it out of engagement with the end of the screw 40 for a purpose to be hereinafter set forth when the armature 30 approaches the end of the core 28 under the action of the coils 26.

A magnet coil 43 having its axis vertical is carried on the upper side of the platform 7. The armature 44 which coöperates with this magnet coil is pivoted at one end to a post or member 45 carried on the upper side of platform 7. A helical spring 46, having one end secured to a lug formed for the purpose on the upper side of the armature 44 and the other end secured to the lower end of a bolt 47 which is adjustably secured to the platform 5, normally holds the armature in the position shown in Fig. 1. The upward movement of the free end of the armature 44 is limited by its engagement with a screw 48 carried by an arm 49, which is secured to a block 50, carried in turn by an arm 51, which is clamped to two of the posts 6. A spring arm 52 is carried from the under side of block 50. The arm 52, by reason of its resiliency, normally bears against an adjustable contact member 53 carried by the arm 49. The outer end of the spring arm 52 is extended so that it will be engaged by the outer end of the armature 44 in its downward movement occurring when it is attracted by the coil 43. The movement given to the arm 52 by this downward movement of the armature 44 will cause the contact to be broken between the arm and the contact member 53. A rod 54 pivotally connected to the upper side of the armature 44, and having its upper end guided by the platform 5 through an aperture in which it passes, carries a pair of adjustable collars, 55 and 55'. When the armature 44 is attracted by the coil 43 and the rod 54 is moved downward, the collar 55 will engage with the ratchet wheel 25, and at the same time the collar 55' will engage the offset end 37 of the pivoted member 36 and through it move the pawl 35 out of engagement with the ratchet wheel 25, thus freeing the ratchet wheel 25 from its engagement with the dog 38 and pawl 35 for a purpose to be herein-after determined.

A rod 56 extends upward from the platform 7. The yoke member 57 of a clutch surrounds this rod. The yoke member 57 has a pawl 58 pivoted to it. The inner end of the pawl is sharpened and normally engages the rod 56, as is clearly shown in Fig. 130

3, by reason of the fact that the outer end overbalances the inner end. A rod 59 extends upward from the cross head 18' adjacent the rod 56 passing through an aperture formed for the purpose in the outer end of pawl 58. Collars 60 and 61 are adjustably secured to the rod 59 at opposite sides of the pawl 58. When the cross head 18' and thereby the rod 59 is moved upward, 10 the clutch 57 offers no resistance to the movement of the rod 59, the rod 59 passing loosely through the aperture in one end of the pawl 58 until the underside of the pawl 58 is engaged by the collar 61, after which 15 the upward movement of the cross head 18' carries the clutch 57 with it. The downward movement of the cross head 18', and consequently of the electrode 16, is limited, however, by the engagement of the collar 20 60 with the upper side of the pawl 58; this engagement causes the pawl 58 to grip the rod 56 more firmly.

In order that the clutch 57 may be released from its engagement with the rod 25 56 and the cross head 18' be lowered whenever it becomes desirable to do so, I have provided a cross head 62 of insulating material which slides upon the rod 56. This cross head is mounted upon the upper end 30 of an operating rod 63. The lower end of this rod passes through apertures formed for the purpose in platform 7, annular member 8 and plate 10, and is provided at its lower end with a button 64 by which it can 35 be grasped. A spring catch 65 normally holds the cross head 62 elevated in the position shown in Fig. 3. Upon pulling this cross head down upon the yoke 57 the locking engagement between the clutch and the 40 rod 56 will be broken and the cross head 20 and parts connected thereto can then be lowered.

A cylindrical casing 66, which may be formed out of sheet metal, extends between 45 the platforms 5 and 7 inclosing the operating mechanism of the lamp. Another cylindrical casing 67, of somewhat greater diameter than the casing 66, extends from the annular member 8 upward somewhat above 50 the platform 5. The lower end of the outer casing 67 is turned in to form a flange 67' which is removably clamped against the under side of the annular member 8 by screws 68. The casings 66 and 67 are secured together by means of one or more pipe or conduit members 69, which extend 55 between apertures formed in the casings 66 and 67. Air for ventilating the interior mechanism of the lamp passes through the 60 bores of these tubular members 69.

The difference in the diameters of the casings 66 and 67 results in the formation of an annular space or chimney through which the heated gases or vapors from the arc between the electrodes 13 and 16 can escape 65

from the lamp. As is clearly shown in Fig. 1, the outer edge 1' of cap or top 1 is turned down so as to form a hood which prevents moisture or dirt from entering the annular space between the casings 66 and 67.

Lugs 70 which depend from the under side of the annular member 8 are formed with threaded apertures through which screws 70' pass. These screws detachably secure in place a globe 71 which is formed of transparent or translucent material, such as glass. Spaces 72 exist between the top of the globe 71 and the annular member 8 through which the air necessary for the proper operation of the arc may enter. The products of combustion from the arc, mixed with a certain amount of air which enters through the spaces 72, pass upward through the tubular passage formed by the flange 8' into the space between the platform 7 and the annular member 8, and thence through the annular space between the casings 66 and 67, finally leaving the lamp through the space between the outer edge of the casing 67 and the cap or top 1.

Brackets 73 secured to the under side of the cap or top 1 hold a resistance coil 74. A bushing 75 carried by one of the posts 6 has a sliding electrical contact with the rack bar 21 and through it with the electrode 16.

For a proper understanding of the circuit connections of the lamp reference should be had to the diagram shown in Fig. 6. Referring to the diagram, a conductor 76 extends from the binding post 3 to the lower electrode 16 of the lamp. One terminal of the coils 26, which are in series with one another, is connected to the line 76, at the point 77. The other terminal of the coils 26 is connected to the contact member 39. One terminal of the resistance conductor 74 is connected to the line 76 at the point 78. The other terminal of the resistance conductor 74 is connected to the plate 49 by a conductor 79. A conductor 80 connects the plate 41 with line 79 at the point 81. A conductor 82 connects the binding post 3' with one terminal of the magnet 43. A conductor 84 connects the plate 42 with the line 82 at the point 83. The other terminal of the coil 43 is connected to the plate 10 by a conductor 86.

The movable parts of the lamp mechanism are shown in the drawings and diagram in the positions they occupy when the lamp is out of circuit. When the binding posts 3 and 3' are connected in a proper operating circuit, current will flow from the binding post 3' through the conductor 82, conductor 84, plate 52, contact member 53, plate 49, line 79 to the point 81; thence the current will divide, one branch flowing through the resistance conductor 74 to the line 76, and thence to terminal 3, and the other through the conductor 80, plate 41, 120

contact screw 40, plate 39, windings of the coils 26 through the line 76 to the terminal 3. The passage of current through the windings 26 will energize them and cause them to attract the armature 30. When the armature 30 is attracted the pawl 35 will engage the ratchet wheel 25 and rotate it in the direction shown by the arrow in Fig. 2. Near the inner limit of the movement of the armature 30 the arm 42 will engage the plate 39 and move it away from the contact screw 40. This will break the circuit through the electro-magnets 26, which will be deenergized and allow the armature 30 to return to its original position. The movement of the wheel 25 in the opposite direction to that indicated by the arrow in Fig. 2 will be prevented at this time by the dog or pawl 38. As soon as the armature 30 moves outward the plate 39 will by its resiliency again move into contact with the screw 40, thus reenergizing the magnet coils 26. The armature 30 will again be attracted and the wheel 25 given a further movement in the direction indicated by the arrow in Fig. 2. The rotation of the ratchet wheel 25 causes a corresponding rotation of the spur gear wheel 24 in a direction which elevates the rack bar 21, and consequently the electrode 16. This intermittent energization of the magnet coils 26 and step-by-step rotation of the ratchet wheel 25 is continued until the electrode 16 strikes against the electrode 13. When this occurs current will begin to flow from the terminal 3' through the conductor 82, windings of the electro-magnets 43, conductor 86, plate 10, electrode 13, electrode 16, conductor 76 to the terminal 3. The passage of current through the windings of the electro-magnet 43 will cause it to attract the armature 44. When the armature 44 is attracted the downward movement of its free end moves the contact plate 52 away from the contact member 53. This breaks the circuit which includes the resistance conductor 74 and the one which includes the windings of the magnets 26. At the same time the downward movement of the rod 54 will cause the collar 55 to move the dog 38 out of engagement with the ratchet wheel. In a similar manner the collar 55 will engage the extension 37 of the arm 36 and thereby move the pawl 35 out of engagement with the wheel 25, thus freeing the wheel 25 which will begin to rotate, under the weight of the bar 21 and parts carried thereby, in a direction opposite to that indicated by the arrow in Fig. 2. As the electrodes 13 and 16 separate an arc is drawn between them. As the rod 59 begins to descend the collar 61 will move away from the pawl 58 which will thereby clamp the rod 56 between it and the yoke member 57. After a movement of the rod 59 equal to the play of the pawl 58 between the collars 60 and 61, the collar 60 will strike against the upper end of the pawl 58. As this engagement operates to more firmly force the inner end of the pawl 58 into engagement with the rod 59, the downward movement of the rod 59, and thereby of the electrode 16, is checked. It will thus be readily seen that the separation of the electrodes 13 and 16 occurring after their contact is always equal to the play of the pawl 58 between the collars 60 and 61, and in consequence the arc struck after each feeding operation with any given adjustment of the collars 60 and 61 is always of a constant length. When the flow of the current through the windings of the electro-magnet 43 is interrupted in any manner the armature 44 will be moved upward by the spring 46, allowing the spring contact 52 to engage the contact member 53. If after or at the time at which this occurs the terminals 3 and 3' are connected in a suitable circuit the electro-magnets 26 will be energized and deenergized in the manner hereinbefore described until the electrodes 13 and 16 again engage. As the rod 59 moves up, the collar 61 will engage the under side of the pawl 58 and carry it and the yoke member 57 upward a distance equal to the difference between the distance separating the ends of the electrodes 13 and 16 at the beginning of the feeding operation and the play of the pawl 58 through the collars 60 and 61. When current begins to flow again through the windings of the electro-magnet 43 the armature 44 will again be attracted and the electrode 16 will again separate from the electrode 13 drawing an arc of a predetermined length.

It has been found that a consuming electrode 16 can be employed in lamps of this character which wastes away so slowly that a feeding operation of the lamp is not required during the normal period of operation. When, however, it becomes necessary or desirable to employ a lamp in which the electrode may be fed at intervals as it wastes away, it is only necessary to employ means for short-circuiting or otherwise de-energizing the windings of the electro-magnet 43 whenever a feeding operation is necessary.

Most of the products of combustion from the arc between the electrodes 13 and 16 are carried up by the draft created by the beat of the arc through the tubular member 8' into the space between the platform 7 and the annular member 8, and thence through the annular space between the casings 66 and 67 and the upper end of the lamp when they are discharged into the atmosphere through the space between the end of the casing 67 and the cap. The casing or shell members 66 and 67 may be regarded as forming a double-walled vertical annular

casing. The space or chamber between the walls of this casing forms a chimney passage through which the arc products are carried by natural drafts. The member 7 forms a horizontal partition which prevents the arc products from passing into the space in which the electrode moving mechanism is located.

More or less of the products of the arc 10 may condense upon the interior parts of the lamp. In order to remove this condensed deposit the screws 68 may be loosened and the casing 66 and 67 removed from the lamp, whereupon the various parts of the lamp 15 may be readily cleaned.

I have found that where the positive electrode is formed out of any conducting material, such as copper or the like, in order to prevent a rapid destruction of the electrode 20 by oxidization or otherwise, it is necessary that the electrode be so arranged that it will not be heated to too high a temperature by the arc.

In the lamp hereinbefore described and 25 illustrated I have formed the positive electrode 13 out of a copper pencil or rod connected to a plate also made of copper or other material which is a good conductor of heat. In consequence of this the heat generated at the arc end of the pencil is rapidly conducted along the length of the pencil to the plate 10. As the plate 10 has a very considerable heat-radiating or dissipating capacity the heat which is thus conducted 30 away from the pencil 13 to the plate 10 is rapidly dissipated. This insures the temperature of the pencil 13 being maintained at a much lower point than would be the case if the plate 10, which is both a good 35 conductor and a good radiator of heat, were not employed. The heat-dissipating capacity of the electrode should not, however, be increased beyond certain limits, at least with many substances which may be employed in 40 the consuming negative electrode, as they give off fumes which will condense in large amounts upon the positive electrode if it is too cool. These fumes are in many cases more or less non-conducting and when condensed on the electrode interfere in various 45 ways with the proper operation of the lamp. It will of course be understood that the pencil 13 and plate 10 connected thereto is only one form of non-consuming electrode having 50 a proper heat-dissipating capacity and that this feature of my invention can be embodied in other forms.

I have found that the use of the insulating jacket or jackets surrounding the pencil 55 is desirable in many cases to prevent a tendency of the arc to run up the side of the electrode, particularly as it is difficult to prevent an occasional deposit of condensed material from the arc upon the arc end 60 of the pencil which is but poorly conducting.

The annular space 15' formed at the lower end of the positive electrode between the pencil 13 and insulating jacket 15 is of advantage as it prevents the formation of a slag which might otherwise be created and which might cause the agglomeration of the end of the pencil and jacket along with some of the material condensed from the arc.

While I have hereinbefore described and illustrated in detail one embodiment of my invention, it is not intended that my invention shall be limited to this particular embodiment as it will be apparent to any one skilled in the art that many changes may be made in the form of my invention without departing from its spirit.

What I claim as new and desire to secure by Letters Patent of the United States, is,

1. In an arc lamp, a movable electrode, a feeding mechanism therefor comprising a member moving with said electrode, a stationary rod or post, a clutch including a yoke surrounding said rod or post, and a pawl normally engaging said rod and extending between stops carried by said member whereby a predetermined movement of the member in one direction causes a corresponding movement of the clutch relative to the post and the clutch serves to limit the movement of the member in the opposite direction, and manually actuated means for moving said clutch relative to said rod in the direction opposite to that in which the clutch is moved by said member.

2. In an arc lamp, an electrode feeding mechanism comprising a rod or bar, an arc length limiting clutch mounted thereon and normally free to move in one direction only, and means for engaging said clutch to move it in the opposite direction.

3. In an arc lamp, a rod or bar, a clutch comprising a yoke surrounding said rod or bar, and a pawl pivoted to the yoke, means for engaging one end of the pawl to release the clutch from the rod to move it in one direction, and means for engaging the yoke to move the clutch in the opposite direction.

4. In an arc lamp, an arc length limiting clutch, a member upon which it is mounted, a connection between the clutch and the feed mechanism of the lamp whereby the movement of the feed mechanism in one direction will move the clutch with it, while a predetermined movement of the feed mechanism in the other direction will cause the clutch to engage the supporting member and limit the movement of the feed mechanism in said opposite direction, and means for rendering the engagement between the clutch and the supporting member inoperative.

5. In an arc lamp, a pair of electrodes, a feeding mechanism therefor comprising a movable rack bar, an electrode moving with said rack bar, a second electrode, a gear wheel engaging said rack bar to move it and

thereby move the electrodes together against the action of gravity, an intermittently actuated electromagnet for rotating said gear wheel, means connecting said electromagnet the winding of which is in series with said electrode and said gear wheel, means actuated by the passage of current between the electrodes for rendering said connecting means inoperative, and means limiting the

movement of the rack bar after said connecting means are rendered inoperative.

In witness whereof, I have hereunto set my hand this 7th day of November, 1903.

JOHN T. H. DEMPSTER.
